UNITED STATES PATENT OFFICE.

OSCAR H. CHILD AND LAROE M. COLLINS, OF BOSTON, MASSACHUSETTS.

ELEVATOR.

SPECIFICATION forming part of Letters Patent No. 268,623, dated December 5, 1882.

Application filed May 8, 1882. (No model.)

To all whom it may concern:

Be it known that we, OSCAR H. CHILD and LAROE M. COLLINS, both of Boston, in the county of Suffolk and State of Massachusetts, 5 have invented jointly new and useful Improvements in Elevators, of which the following, taken in connection with the accompanying drawings, is a specification.

Our invention relates to self-closing doorways and hatchways for elevators; and it consists, first, in the combination, with the elevator-well and a car arranged to move vertically therein through two or more stories of a building, of a flexible apron connected by one end 10 to the car and at its other end to the top or bottom of the well, and adapted to move with the car in such a way that, in whatever position the car may be, all of the doorways or openings to the well, except the one opposite which 15 the car may be, will be so closed or guarded that it would be impossible for a person to fall into the well.

It further consists in the combination, with an elevator-well and a car arranged to move 20 vertically therein, of two flexible aprons arranged upon opposite sides of the well, and each attached by one end to the car and at the other end to the top or bottom of the walls of the well, and one or more hatch-covers attached 25 to said aprons or guards and adapted to be moved up and down as the car is moved, and to close the openings through the floors when 30 in their normal position.

Figure 1 of the drawings is a vertical section 35 on line $x x$ on Figs. 2 and 3. Fig. 2 is a horizontal section on line $y y$ on Fig. 1. Fig. 3 is a horizontal section on line $z z$ on Fig. 1. Fig. 4 is a vertical section on line $w w$ on Fig. 1, looking toward the left hand. Fig. 5 is a similar section on line $v v$ on Fig. 1, looking toward the right hand, and Fig. 6 is a vertical section 40 illustrating a modification of our invention, in which entrances are arranged upon two sides of the well and hatch-covers are applied below 45 as well as above the car.

$A A$ are four posts, extending from the bottom of the basement up through the floors B , C , D , and E , and to a point some distance above the upper floor, E , and forming the corners of the elevator-well.

F are two posts, arranged centrally be-

tween two of the posts A , upon opposite sides of the well, and each provided with the inwardly-projecting rib or lip a , which serves as a guide for the car in a well-known manner.

G is the car, suspended by the wire rope b from the pulley H in a well-known manner.

$I I$ are flexible aprons, composed in the case illustrated of a series of slats or bars, $c c$, extending horizontally across one side of the well, 60 and arranged to be moved up and down in grooves $d d$ formed in the posts $A A$, and connected together by means of the flexible bands or chains $e e$, in such a manner that when said bands or chains are extended the bars $c c$ will 65 be about an equal distance apart, as shown in the lower parts of Figs. 1 and 6. One end of each of the bands or chains $e e$ is made fast to the car G , and the other end is secured to some fixed part of the framing of the building, either 70 at the top or bottom of the well, according as to whether it is above or below the car.

In Fig. 1 the opening J , which opens to the well from the sidewalk f , is closed, when the car moves up, by the short apron I' , composed 75 of the bars $c' c'$, secured to the straps or chains $e' e'$, and moved upward automatically by the weights $g g$, acting through the cords $h h$ and pulleys $i i$, as shown in Figs. 1 and 5.

L are hatchway-covers secured to, held in 80 suspension by, and adapted to be moved up and down with the flexible aprons $I I$, all so arranged that when said aprons are extended a hatchway-cover, L , shall close an opening in each floor below the car when it is at the top 85 of the well, or above it when it is at the bottom of the well, as illustrated in the lower part of Fig. 6.

As the car G is moved upward it comes in contact with the first pair of bars, $c c$, above it, 90 when they are carried upward with the car till they come in contact with the second pair of bars, $c c$, and they are moved upward, and so on till all the bars $c c$ that are above the car are packed close together, as shown in Figs. 1, 4, 95 5, and 6. At the same time the hatch-covers L that are above the car are carried upward and occupy the position shown in Figs. 1 and 6, and the bars $c c$ and the hatchway-covers that are below the car are moved into the positions 100 shown in Fig. 6. If the car be now moved downward, the aprons below the car will be col-

lapsed, and the bars *c c* and covers *L* will be packed together in the basement below the lower opening, while the flexible guards *I I* above the car will be extended and the covers *L* will be brought into the proper positions to close the openings in the floors *D* and *E*. In case of the arrangement shown in Fig. 1, when the car descends to a position with its platform on a level with the sidewalk *f* the bars *c' c'* are all moved down by the car into the basement, the weights *g g* being raised to permit such downward movement, and when the car is moved upward again the weights *g g* descend again and cause the bars *c' c'* to rise to the position shown in Fig. 1.

Instead of the bars *c c* and bands or chains *e e*, a flexible apron of cloth or netting may be used, if desired; but we prefer the bars and bands or chains, as shown.

With our device properly applied to an elevator-car all danger of accidents from persons falling down the well will be obviated, as no opening to the well through which a person could fall will be unguarded at any time, except the one opposite to which the car is standing or passing.

What we claim as new, and desire to secure by Letters Patent of the United States, is—

1. In combination with an elevator-well and a car arranged to move vertically therein, a flexible apron connected at one end to the car and at the other end to a fixed portion of the framing at the top or bottom of the well, substantially as and for the purposes described.

2. The combination of an elevator-well, a car arranged to be moved vertically therein, flexible aprons arranged upon opposite sides of the well, and each attached by one end to the car and at the other end to some fixed portion of the framing at the top or bottom of the well, and one or more hatch-covers secured to said aprons or guards, and adapted to operate substantially as and for the purposes described.

In testimony whereof we have signed our names to this specification, in the presence of two subscribing witnesses, this 4th day of May, A. D. 1882.

OSCAR H. CHILD.
LAROE M. COLLINS.
